United States Patent Office

Des. 232,076
Patented July 16, 1974

232,076

BOTTLE OR SIMILAR ARTICLE

Albert Jacob, Paris, France, assignor to Colgate-Palmolive Company, New York, N.Y.

Filed Sept. 27, 1972, Ser. No. 292,766

Term of patent 14 years

Int. Cl. D9—01

U.S. Cl. D9—42

FIG. 1

FIG. 3

FIG. 2

FIG. 4

FIG. 5

FIG. 1 is a top plan view of a bottle or similar article embodying my new design;

FIG. 2 is a side elevational view, the opposite side being a mirror image of the side shown;

FIG. 3 is an elevational view looking from the right of FIG. 2;

FIG. 4 is an elevational view looking from the left of FIG. 2; and

FIG. 5 is a bottom plan view thereof.

I claim:

The ornamental design for a bottle or similar article, as shown and described.
